UNITED STATES PATENT OFFICE.

SAMUEL L. HOWARD, OF CHICAGO, ILLINOIS.

PRINTING-PRESS-TYMPAN BAIL.

1,150,767.

Specification of Letters Patent. Patented Aug. 17, 1915.

Application filed May 28, 1915. Serial No. 30,917.

To all whom it may concern:

Be it known that I, SAMUEL L. HOWARD, a citizen of the United States, and resident of Chicago, in the county of Cook and State 5 of Illinois, have invented a new and Improved Printing - Press - Tympa Bail, of which the following is a full, clear, and exact description.

Among the principal objects which the 10 present invention has in view are: to provide a printing press with means for preserving tympan sheets and the make-ready secured thereon when the same is removed from service on the press; and to provide a 15 simple, efficient construction for maintaining the original registration of the make-ready.

Drawings.—Figure 1 is a perspective view of a printing press platen having a tympan 20 bail constructed and arranged in accordance with the present invention, said bail being shown in service relation. Fig. 2 is a perspective view on an enlarged scale, showing a bail constructed and arranged in accordance with the present invention; Fig. 3 is a detail view on an enlarged scale, showing an edge fragment of the platen, a bail constructed in accordance with the present invention in service relation thereto, and a 25 clamp partially holding a tympan sheet on said bail, said figure being a section taken as on the line 3—3 in Fig. 1; Fig. 4 is a section on a similar scale, taken as on the line 4—4 in Fig. 1; and Fig. 5 is a section on a 30 similar scale, taken as on the line 5—5 in Fig. 1.

Description.—As seen in the drawings, the platen 10 is provided at the lower edge with a swinging bail 11 of conventional form. 40 When the bail 11 is depressed, as seen in Fig. 1 of the drawings, the tympan sheet 12 is clamped in service relation to the platen and is there held firmly. The upper or outer edge of the tympan sheet 12 when 45 mounted in accordance with the present invention, is clamped to the bail 13 by the clamp bar 14. To this end, as seen best in Figs. 3 to 6 inclusive, the tympan sheet 12 is folded over the upper and outer edges of the bail 13 and in this position drawn taut.

To hold the sheet 12 on the bail 13 and when the said bail is swung to relieve the tension on the sheet 12, or to permit access to the under side thereof, is the function of 50 the bar 14. The bar 14 is supported on the

bail 13 by pins 15, which extend through perforations 16 in the said bail. The pins 15, as seen best in Fig. 4 of the drawings, are pointed to puncture or pierce the material forming the sheet 12 where it is stretched across the entrance to the said perforations. The pins 15 also operate as pivots on which to swing the locking levers 17 into service position. Each lever 17 has a handle 18 extended in the same plane with the body 65 portion of the lever and a clip hook 19 extended from the side thereof adjacent the said bail 13, the clip hooks 19 having each a blade-like extension to cut a slot in the tympan sheet and to enter recesses 20 provided in the bail 13.

Operation.—The tympan sheet 12 is disposed on the platen 10 and there secured by the bail 11 in the conventional manner. At the upper or outer edge of the platen, the 75 tympan sheet 12 after being drawn taut is passed over the bail 13 and around the same to extend between the edge of the platen 10 and said bail, as shown best in Figs. 3 to 5 inclusive. After the bail 13 has been lifted, 80 it will be seen that as the same is swung to the service position shown in Fig. 1 of the drawings, the tension on the sheet 12 is augmented or increased, drawing the said sheet more evenly and tighter over the platen 10. 85 After the sheet 12 is thus set, the clamp bar 14 is placed on the bail 13, the pins 15 being forced through the outer section of the sheet 12, as seen best in Fig. 4 of the drawings. The levers 17 are disposed in a standing or 90 perpendicular position, such as shown at the left of Fig. 2 and also as shown in Fig. 3 of the drawings. The edge of the hook 19 is sharpened to cut through the sheet 12 and is preferably elongated to hold the said sheet 95 12. When the levers 17 are disposed as shown in Figs. 4 and 5 of the drawings, or at the right of Fig. 2 of the drawings, they avoid other parts of the printing press, while the same is operated.

If the tympan sheet 12 having been set, registering pins or make-ready is required, the said sheet may be lifted away from the face of the platen, the bail 13 swinging on its pivot to this effect. If the operator desires, the sheet may be removed from the platen without disturbing the make-ready or registering pins thereon. When in the course of operation, the attendant wishes to replace the sheet 12 with the make-ready, 100 105 110

this is usually accomplished by first adjusting the perforated end of the said sheet on the bail 13 and to the bar 14 and levers 17 thereof. In making this adjustment care is exercised to dispose the hooks 19 of the levers 17 in the cuts previously formed thereby in the said sheet. The readjustment of the sheet being thus secured at the upper end, the bail 11 is tightened over the lower end of the sheet and the tympan sheet will be found to be adjusted to the work to be performed by it.

Claims:

- 15 1. A bail as characterized comprising a swinging bar having a series of socket members; a clamp bar disposed on said swinging bar; and a plurality of levers pivotally mounted on said clamp bar, said levers hav-

ing each a clip hook for insertion within one of said socket members.

2. A bail as characterized comprising a swinging bar having a series of socket members; a clamp bar disposed on said swinging bar; a plurality of levers pivotally mounted on said clamp bar, said levers having each a clip hook for insertion within one of said socket members; and a series of locating pins mounted on said clamp bar for engaging said bail.

In witness whereof I have signed my name to this specification in the presence of two subscribing witnesses.

SAMUEL L. HOWARD.
